Roy Benson Hall INVENTOR,

Roy Benson Hall.

UNITED STATES PATENT OFFICE

ROY BENSON HALL, OF HAMMOND, INDIANA

PRESS CONSTRUCTION

Application filed August 22, 1930. Serial No. 477,141.

My invention relates to improvements in press constructions, and it consists in the combinations, constructions, and arrangements herein described and claimed.

5 An object of my invention is to provide a press construction which is light in weight, convenient in use, and economical in operation.

10 A further object of my invention is to provide a device of the character described having a pivotally mounted head which may be swung outwardly when it is not being used.

15 A further object is to provide means whereby the drum may be lowered a predetermined distance for the purpose of enabling the swinging head to be moved out of the way when the material has been pressed and is ready to be unloaded.

20 Other objects and advantages will appear in the following specification, and the novel features of the invention will be particularly pointed out in the appended claims.

25 My invention is illustrated in the accompanying drawings, forming part of this application, in which

Figure 1 is a top plan view of a press embodying my invention, and

30 Figure 2 is a front elevational view showing, partly in section, the device depicted in Figure 1.

35 In carrying out my invention, I make use of a press construction having a swinging head 1, guide columns 3, a perforated drum 5 for holding the material 8 while it is being pressed, and a driving ram or piston 9 which is adapted to move upwardly for the purpose of pressing the material 8 and thereafter ejecting it from the drum 5.

40 One end of the swinging head 1 may be pivotally mounted around one of the guide columns 3 substantially as shown and the other end may be adapted to be locked in operating position around the other guide column by any suitable means, such as, for instance, a locking bar 2.

45 The drum 5 may be slidably mounted on the guide columns 3. The guide columns 3 may, if desired, be provided with recessed collar members 4 adapted to limit the movement of the drum 5. These collar members

may be secured to the columns 3 by threaded bolts or any other suitable means adapted to rigidly secure the collar members 4 at any desired height on the guide columns 3. The drum 5 may be provided with an annular 55 flange adapted to fit within the recessed collar members, substantially as shown. The drum 5 may be provided with a close fitting sealing plate 7 which is adapted to be placed upon the material when the drum is loaded. 60 This plate serves to seal the space between the drum 5 and the head 1 when the material is being pressed.

65 From the foregoing description of the various parts of the device, the operation thereof may be readily understood. When the pressure on the piston 9 is removed, the drum 5, with its plate 7, slides downwardly as far as the grooved collar members permit. This action enables the swinging head 1 to be 70 swung outwardly and out of the way after the locking bar is removed from the swinging head.

I claim:—

1. A press for extracting liquids including 75 a ram construction, a swinging head for said press rotatably mounted and adapted to be swung horizontally above said ram construction, a pair of guide columns connecting said head with said ram construction, and a perforated drum slidably carried by said guide columns between said head and said ram construction, said drum being provided with a flanged top cover plate adapted to seal the upper portion of said drum when said drum 80 is loaded and said material is being pressed. 85

2. A press for extracting liquids including 90 a ram construction, a swinging head for said press rotatably mounted and adapted to be swung horizontally above said ram construction, guide columns connecting said head with said ram construction, and a perforated drum slidably carried by said guide columns between said head and said ram construction, said guide columns being provided with stop 95 means for limiting the movement of said drum on said columns for the purpose of removing pressure on said head when the ram of said ram construction is moved downwardly. 100

ROY BENSON HALL.
